UNITED STATES PATENT OFFICE.

WALTER H. HIMES, OF GROVE CITY, PENNSYLVANIA, ASSIGNOR TO HIMES COHEN
TRACTOR CO., OF GROVE CITY, PENNSYLVANIA.

TRACTOR-PLOW.

1,316,235.

Specification of Letters Patent. Patented Sept. 16, 1919.

Application filed March 1, 1919. Serial No. 280,121.

To all whom it may concern:

Be it known that I, WALTER H. HIMES, a citizen of the United States, residing at Grove City, in the county of Mercer and 5 State of Pennsylvania, have invented certain new and useful Improvements in Tractor-Plows, of which the following is a specification.

This invention relates to improvements 10 in tractor plows.

The main objects of this invention are:

First, to provide an improved tractor plow of the alternating type with means for simultaneously adjusting both plows to 15 regulate the depth of the furrow.

Second, to provide an improved plow support or hanger means which permits lateral movement of the plow to pass an obstruction and at the same time normally 20 hold the plow in its proper upright working position.

Third, to provide an improved plow having these advantages which is comparatively simple in structure and at the same 25 time strong and durable.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing forming a part of this specification, in which:

Figure I is a side elevation of a plow embodying the features of my invention, one 40 of the plows being raised and the other lowered, various of the parts being shown conventionally for convenience in illustration.

Fig. II is a detail plan view.

Fig. III is a rear elevation with parts shown in broken section.

Fig. IV is an enlarged detail side elevation of the means for regulating the depth of the furrow.

In the drawing, similar reference characters refer to similar parts throughout the several views.

Referring to the drawing, 1 represents the running gear frame, 2 the traction or

driving wheels, and 3 the steering wheels. 55 The driving connection and the steering connections for the wheels form no part of this invention and are therefore not described herein.

4 represents an internal combustion engine from which power is derived. The plows 5 are provided with beams 6 which are connected to the draft bar hangers 7 depending from the frame by the draft bars 8. The draft bars are pivoted to the 65 hangers at 9 and to the front ends of the plow beam at 10. The hangers are provided with brace rods 11. Adjusting screws 12 are provided for raising and lowering the front ends of the beams 6. The adjusting 70 screws engage collars 13 secured to the beams at the pivot points thereof.

An adjusting shaft 14 is disposed longitudinally of the frame and provided with beveled gears 15 meshing with beveled gears 75 16 on the attaching screws. The shaft 14 is provided with a hand wheel 17. The rotation of this shaft 14 raises the front ends of the plow beams thus regulating the depth of the furrow, and the beams of both plows 80 are simultaneously raised and lowered so that a uniform adjustment is secured therefor.

The plows are raised from and lowered to the ground and supported laterally by a 85 mechanism comprising supporting bars 18 having arms 19 pivotally mounted on the rods 20. These arms are connected by the cross pieces 21, the arms, the cross pieces and bar, as illustrated, being an integral 90 casting. The plow beams are provided with cross arms 22 near the rear ends thereof. The supporting bar and arms have spherical bearing members 23 at their ends. Links 24 having sockets 25 coacting with these 95 spherical bearing members are provided. These links are connected by the crossed springs 26, the springs being connected with the links near the ends thereof. The supporting and adjusting chains 27 are connected to the supporting bars and to the shafts 28 whereby the plows may be raised or lowered. The means for actuating these 100 shafts 28 are not illustrated or described in detail as they form no part of my invention. Manual or power means or both may be provided as desired.

With this arrangement of parts the plows

may be conveniently raised and lowered and are supported to yield laterally to pass an obstruction such as a stone or stump, or in turning a corner side movement is permitted, at the same time the springs return the plow to the neutral position after the obstruction is passed. The plows are maintained in a vertical position even though thrown or deflected to one side.

10 I have illustrated and described my improvements in a simple and practical embodiment. I have not attempted to illustrate certain modifications and adaptations which I contemplate as I believe the disclosure made will enable those skilled in the art to which my invention relates to adapt or embody the same as may be desired.

Having thus described my invention, what I claim as new and desire to secure by 15 Letters Patent, is:

1. In a plow, the combination with a running gear frame, of front and rear wheels alined to travel in a furrow, oppositely disposed alined plows provided with beams, 25 draft bar hangers on said frame, draft bars pivotally mounted on said hangers and pivotally connected to the plow beams, adjusting screws having threaded connection with the front ends of the plow beams 30 whereby they may be raised and lowered, an actuating shaft mounted on said frame, said actuating shaft and adjusting screws being provided with coacting beveled gears whereby the screws are simultaneously actuated 35 to adjust the beams, and independent means for raising and lowering the plows.

2. In a plow, the combination with a running gear frame, of front and rear wheels alined to travel in a furrow, oppositely disposed alined plows provided with beams, 40 draft bar hangers on said frame, draft bars pivotally mounted on said hangers and pivotally connected to the plow beams, adjusting screws having threaded connection 45 with the front ends of the plow beams whereby they may be raised and lowered,

and means for simultaneously adjusting said screws.

3. In a plow, the combination with a running gear frame, of front and rear wheels 50 alined to travel in a furrow, oppositely disposed alined plows provided with beams, draft bar hangers on said frame, draft bars pivotally mounted on said hangers and pivotally connected to the plow beams, and means for simultaneously raising and lowering the front ends of said beams to regulate the depth of the furrow.

4. In a plow, the combination with a running gear frame, of oppositely disposed 60 plows provided with beams, draft bars connected to the plow beams, adjusting screws for the front ends of the plow beams whereby they may be raised and lowered, an actuating shaft mounted on said frame, said 65 actuating shafts and adjusting screws being provided with coacting beveled gears whereby the screws are simultaneously actuated to adjust the beams, and independent means for raising and lowering the plow. 70

5. In a plow, the combination with a running gear frame, of oppositely disposed 75 plows provided with beams, draft bars connected to the plow beams, adjusting screws for the front ends of the plow beams whereby they may be raised and lowered, and means for simultaneously adjusting said screws.

6. In a plow, the combination with a running gear frame, of oppositely disposed 80 plows provided with beams, draft bars connected to the plow beams, and means for simultaneously raising and lowering the front ends of the beams to regulate the depth of the furrow.

In witness whereof, I have hereunto set my hand and seal in the presence of two witnesses.

WALTER H. HIMES. [L. S.]
